UNITED STATES PATENT OFFICE.

HUGO LENTZ, OF BERLIN, GERMANY.

TURBINE-DRIVEN LOCOMOTIVE.

No. 823,130.

Specification of Letters Patent.

Patented June 12, 1906.

Application filed August 10, 1905. Serial No. 273,508.

To all whom it may concern:

Be it known that I, HUGO LENTZ, a subject of the German Emperor, residing at Berlin, Germany, have invented a new and useful 5 Turbine-Driven Locomotive; and I do hereby declare the following to be a full, clear, and exact description of the same.

The object of this invention is the production of a turbine-driven locomotive employing 10 several turbine-wheels, preferably one for each wheel, and in which the available power or pressure of the steam or other pressure medium is more evenly employed.

In carrying out my present improvements 15 I provide each of two or more driving-wheels or pairs of driving-wheels with one or more turbine-wheels, and I also provide a plurality of nozzles, one for each turbine-wheel, and all supplied from the same steam-chamber for 20 the purpose of simultaneously subjecting each turbine-wheel or pair of turbine-wheels to an equal or substantially equal pressure fall or power effect.

Prior to my present invention, so far as I 25 am aware, it has not been proposed to independently subject the several turbine-wheels of a locomotive to the action of the steam in multiple, as hereinafter described by me; but (as, for example, see German Patent No. 30 156,088) prior inventors have connected the several turbine-wheels in series and have then utilized the steam-pressure at the different stages to operate upon the several turbine-wheels successively.

35 The accompanying drawings show side and sectional views of one adaptation of my present invention.

Figure 1 is a side view of a portion of a locomotive with the arrangement of steam-chambers, nozzles, turbine-wheels, &c., preferred by me. Fig. 2 is a section on line 1 2 of Fig. 1. Fig. 3 is a section on line 3 4 of said Fig. 1. Fig. 4 is a section on line 5 6, and Fig. 5 is a section on line 7 8, of said Fig. 1.

40 *a a a* indicate the axles connected to the driving-wheels, and *b' b' b'* indicate turbine-wheels which impart motion to the driving-wheels. The turbine-wheels may, if desired, be directly connected with the driving-wheels. 45 *a a a* indicate the axles connected to the driving-wheels, and *b' b' b'* indicate turbine-wheels which impart motion to the driving-wheels. The turbine-wheels may, if desired, be directly connected with the driving-wheels. 50 themselves or may, as shown by me, be fixed upon the axles, preferably at or near a point midway between each pair of driving-wheels.

55 By reference to Fig. 2 it will be seen that I may connect two turbine-wheels, located side by side, upon each axle, and I may subject each of these pairs of turbine-wheels in se-

ries to the pressure of the steam or may divide the jets of pressure medium between the two members of each pair.

It will be observed that, as shown in Fig. 1, 60 each turbine-wheel (or pair of turbine-wheels) *b' b' b'* is operated upon by a separate nozzle *f' f' f'*, all of which lead off from a steam-chamber *e*, which is common to all of the nozzles. The steam-chamber referred to 65 runs along both sides of the several turbine-wheels and is connected with or formed integral with the several turbine casings or shells, which are separated, as shown, and which are journaled upon the axles of the 70 several driving-wheels or pairs thereof.

Steam is supplied to the chamber *e* through a pipe or conduit *c* and is controlled by a valve *d*. The source of steam-supply will be the boiler *y*, carried by the locomotive, 75 and the connections from said boiler to the conduit may be of any suitable form and direct or indirect.

After its action, preferably in multiple, as described, upon the turbine-wheels *b' b' b'*, 80 the steam passes into an exhaust-chamber *g*, formed along both sides of the turbine-wheels and common to all of them above the axles *a*. The exhaust-steam is led into the opposite passage of the exhaust-chamber 85 through the various canals or between the various steam-directing walls, as shown in Fig. 2, as indicated by the arrows.

The exhaust-chamber *g* also acts as an air-jet condenser, and I am thereby enabled to 90 realize all of the advantages due to such feature. For this purpose the forward end of the exhaust-chamber has extensions which form flaring or enlarged mouths or air-receiving ends by bringing the forward inner walls *g* 95 of the chamber close together or otherwise, and the rear ends or extensions of said chamber are contracted or formed to provide reduced discharge-openings *g'*, (reduced in size as compared with the air-receiving ends,) and 100 as a result when the locomotive is running the air enters at *g'* and passing through the two channels of the chamber *g* mixes with the exhaust-steam (the flow of which is directed in the same direction by the steam-directing 105 walls) and condenses such steam to a considerable degree while passing to and out of the contracted exit ends *g'*.

It will be obvious upon examination of the drawings that each turbine-wheel (or pair of such wheels) *b' b' b'* will be separately subjected to the full power effect of the steam

supplied from the common chamber *e* and that all such wheels will be acted upon simultaneously and will be, as it were, elastically coupled together and driven at substantially the same rate of speed, as distinguished from a structure in which the several turbine-wheels are subjected in series to the same jet of steam at different pressures and in which the successive turbine-wheels must be either of different sizes or forms or must be driven at different speeds. In my invention, on the contrary, the various turbine-wheels *b' b² b³* may and preferably will be alike in size and form and will give like results.

15 The use of a single conduit, as *c*, through which all of the nozzles are supplied with steam, in conjunction with acting upon the turbines instead of in series, results in a structure whereby all of the turbines can be proportionately regulated and controlled by a simple throttling, and preferably at one point, by a single valve, such as *d*. So far as I am aware it has been impossible by throttling to regulate or distribute the load when the several turbines were connected in series, as heretofore.

It is, however, not inconsistent with my invention to sometimes employ two or more of the turbine-wheels in series, and where the locomotive has, say, four driven axles these may be arranged in pairs, the two members of each pair being subjected in series to the action of the steam and in elaboration of the construction described in the German patent referred to. The modified form suggested by me will, however, preferably employ a steam-supply chamber, such as *e*, common to all of the nozzles and a single steam-exhaust chamber.

40 Fig. 1 of the drawings shows one turbine-wheel applied to each axle; but I may connect two or more turbine-wheels to each axle in accordance with the well-known Curtis construction and operate upon the several wheels separately or successively.

The steam-supply chamber *e* common to all of the wheels may be of any desired form or size and may, if desired, be replaced by several pipes leading from a larger pipe or all separately and directly connected with the lower end of the conduit *c*.

What I claim is—

1. In a turbine-driven locomotive, a locomotive-truck, a plurality of driving-wheels carried thereby, turbine-wheels, one for each driving-wheel, supply-nozzles, one for each

of said turbine-wheels, a main pipe for supplying pressure medium to all of said nozzles, and a single valve located in said pipe and controlling the supply of pressure medium therethrough to all of the said nozzles simultaneously. 60

2. In a turbine-driven locomotive, a locomotive-truck, a plurality of driving-wheels carried thereby, turbine-wheels, one for each driving-wheel, supply-nozzles, one for each of said turbine-wheels, a chamber from which all of said nozzles lead, a main pipe for supplying pressure medium to said chamber, and a single valve located in said main pipe and controlling the supply of pressure medium therefrom to the chamber aforesaid. 65

3. In a turbine-driven locomotive, a locomotive-truck, a plurality of driving-wheels carried thereby, turbine-wheels, one for each driving-wheel, supply-nozzles, one for each said turbine-wheels, valve connections for supplying pressure to the several nozzles, and a single exhaust-chamber for receiving the exhaust from the several turbine-wheels. 70 75

4. In a turbine-driven locomotive, a locomotive-truck, a plurality of driving-wheels carried thereby, turbine-wheels, one for each driving-wheel, and supply-nozzles, one for each of said wheels, the whole arranged to 80 drive the turbine-wheels in multiple, in combination with pressure-supply connections, and with a single exhaust-chamber for receiving the exhaust from the several driving-wheels. 90

5. In a turbine-driven locomotive, a locomotive-truck, a plurality of driving-wheels carried thereby, turbine-wheels, one for each driving-wheel, the whole arranged to drive the turbine-wheels in multiple, in combination with pressure-supply connections, and with a single exhaust-chamber for receiving the exhaust from the several turbine-wheels. 95

6. In a turbine-driven locomotive, a locomotive-truck, a driving-axle carried thereby, a turbine-wheel operatively connected with said axle, an exhaust-chamber for said turbine-wheel and means, combined with said chamber, for causing a condensation of steam therein. 100 105

In testimony whereof I have signed my name to this specification in the presence of two subscribing witnesses.

HUGO LENTZ.
